CLAIM

The ornamental design for a pneumatic power tool, as shown and described.

DESCRIPTION

FIG. 1 is a perspective view of an embodiment of a pneumatic power tool showing the new design;
FIG. 2 is a top view of the embodiment of FIG. 1;
FIG. 3 is a left side view of the embodiment of FIG. 1;
FIG. 4 is a front view of the embodiment of FIG. 1;
FIG. 5 is a rear view of the embodiment of FIG. 1;
FIG. 6 is a right side view of the embodiment of FIG. 1; and
FIG. 7 is a bottom view of the embodiment of FIG. 1.
The dash-dot broken lines in the drawings show environmental structure that form no part of the claimed design. All other broken lines (dash-dash) depict portions of the pneumatic power tool that form no part of the claimed design.
